VOLTAGE REGULATOR

Erich E. Late and George L. Webb, Fond du Lac, Wis.,
assignors to Wells Manufacturing Corporation, Fond
du Lac, Wis., a corporation of Wisconsin

Filed Mar. 4, 1965, Ser. No. 84,095

Term of patent 14 years

(Cl. D26—13)

FIG. 1

FIG. 2

FIG. 3

FIG. 4

FIG. 1 is a front, top and right end perspective view of a voltage regulator, showing our new design;

FIG. 2 is a rear elevational view, the front being substantially a mirror image thereof;

FIG. 3 is a left end elevational view, the right end being substantially a mirror image thereof; and

FIG. 4 is a bottom plan view thereof.

Portions of the drawing figures are diagonally lined to indicate transparency.

We claim:

The ornamental design for a voltage regulator, substantially as shown and described.
